ALFRED MOORHOUSE AND SAMUEL G. BOWMAN, OF PITTSBURGH, PENNSYLVANIA

PIPE ORGAN

Application filed December 18, 1929. Serial No. 414,843.

The invention relates to pipe organs, and consists in a coordination of means, whereby from a single wind-box one or another pipe will on the pressing of the corresponding key 5 be sounded, according as one or another of a series of stops has previously been drawn out. The objects in view are simplicity of structure and certainty of operation.

In the accompanying drawings Fig. I is a 10 diagrammatic view showing in cross-section the wind-box of an organ and an associated plurality of organ pipes. The organization of the means employed for causing one or another of these pipes to speak when the corresponding key upon the organ manual is de- 15 pressed, in which organization the present invention is found, is here presented in such diagrammatic showing. Fig. II is a fragmentary view showing in side elevation a stop which may be shifted axially from one to another position to control for each pipe the means for causing it to speak; and Fig. III is a fragmentary view showing diagrammatically a key of the organ manual, and indicating means associated therewith for rendering the wind-box effective to cause the pipes of a corresponding stop to speak.

The wind-box 1 may be of any preferred form. In association with it a plurality of 20 pipes is provided. In this instance four pipes, 2, 3, 4, and 5, are shown. These pipes will be understood to be all of one pitch, but to constitute each an element of a separate "stop" of the organ. That is to say,—an organ being regarded as an association of a plurality of instruments or, in usual language, "stops",—each of these pipes, 2, 3, 4, and 5, is to be regarded as a component pipe of one of those instruments, and each is a component of 25 an instrument different from those instruments of which the other pipes are components. When the appropriate key is depressed one of these pipes speaks and that pipe and that pipe only will speak which is part of the "stop" which at the time has been brought into service. It should of course be explained further that if two or more "stops" have been brought simultaneously into service, then on the depressing of the appropriate key, a plurality of the pipes 2, 3, 4, and 5

may speak simultaneously. But for simplicity of explanation the stops may be assumed to be brought into service singly.

Each pipe is controlled by a valve 6. When the valve 6 opens, communication is established between the wind-box and the pipe, air flows from the wind-box through the pipe, and the pipe speaks.

Each valve 6 is subject to pneumatic control, and to that end is integrated with a pressure plate, conveniently in the form of a diaphragm 7 closing a chamber 9. A spring 8 is provided which normally holds the pressure plate extended and the valve in seated position. The chamber 9, of which the pressure plate constitutes one wall, communicates through a lead 10 with a manifold chamber 11, and manifold chamber 11, through ports controlled by the double valve 12, 13, communicates alternately with the open air and the wind-box 1. In contrast to the usual practice of forming ports and passages from each diaphragm chamber (such as the chamber 9) through the walls of the wind-box to an associated manifold, we connect the diaphragm 75 chambers of all of the pipes of a single wind-box to a single manifold, and this is done by means of rubber tubing. That is to say, the manifold 11 serves for all of the illustrated pipes 2, 3, 4, 5. We arrange the manifold 11 within the wind-box 1, and form the leads 10 of lengths of tubing, advantageously of rubber. Rubber tubing does not vibrate to cause undesirable sounds during the operation of the organ. Rubber tubing is cheap to install, 80 and affords lines of communication which are readily accessible for inspection. The lower portion 90 of each chamber 9 (otherwise formed of wood) is conveniently formed of metal, and is provided with a nipple 91 to which tubing may be attached to form the line of communication 10.

On the lower portion 90 a valve 14 is seated for controlling the line of communication 10, and this valve alternately is drawn aside, 85 leaving the line of communication open, or remains free to serve as a check valve, preventing flow through lead 10 in direction from the diaphragm chamber 9 to the manifold 11. In the figure the valve 14 which is 100

associated with pipe 2 is shown in such drawn-aside position; the valve which is associated with pipe 3 is shown in position to serve as a check valve, to prevent flow 5 from that diaphragm chamber 9 toward the manifold 11.

The valve 14 then is so disposed that in its two positions it acts either as a check valve, preventing flow from diaphragm chamber 9 through lead 10, or (alternatively) it closes chest 15. Chest 15 is a pneumatic chest, under the control of one of the stops 26 of the organ manual. When the corresponding stop is draw out (the drawn-out position is indicated in dotted lines in Fig. II), a condition of reduced pressure is established within the chest 15. This condition is such as to draw valve 14 to the position of closure upon chest 15 (the position shown in the drawing to the left, in the case of the valve associated with pipe 2), and in that position it continues, so long as the stop remains in drawn-out position.

The manner in which the stop 26 controls pressure conditions in the chest 15 is indicated in Figure I of the drawings. There is a vent 28 through the wall of the wind box 1, with which vent the chest 15 has communication through the passageway 27. The vent 29 through the wall of the wind box 1 is controlled by a double valve 29, and according as this double valve occupies a position at one or the other of the limits of its range of movement, it establishes communication from the chest 15 either with the wind box 1 or with the open air. By any suitable means, not shown, but easily to be understood, the double valve 28 may be made to respond to the stop 26, to the end that so long as the stop 26 is in the full line position, shown in Figure II, the valve 29 shall be effective to maintain communication between the chest 15 and the wind box 1, and when the stop 26 is shifted from the full line to the dotted line position, the valve 29, in response to such shifting, cuts off communication between the chamber 15 and the wind box 1, and opens communication between the chamber 15 and the open air. Inasmuch as at all other times the pressure in chamber 15 is super-atmospheric, when the chamber 15 is so vented to the open air there is diminution of pressure, and inasmuch as the pressure at the time in the chamber 9 and the pipe connection 10 is super-atmospheric, the effect of so venting the chamber 15 to the open air will be to cause the valve 14 to rise to the position shown to the left in Figure I. When the associated parts are in this position, pipe 2 will 60 speak upon the depression of the appropriate key in the organ manual.

The double valve 12, 13 is controlled by a pressure-plate, conveniently in the form of a diaphragm 16, which constitutes one wall 65 of an ancillary wind-box 17. On one side

the diaphragm 16 is exposed to the atmosphere, on the other side it is exposed to the pressure which obtains in ancillary wind-box 17. A passage 30 from ancillary wind-box 17 is normally in communication by means of ports 31 and 32 with the manifold 11. Ancillary wind-box 17 may be opened to the atmosphere through a vent 33, which vent is controlled by an inwardly-opening valve 18. An electro-magnet 19 when energized is effective to unseat valve 18 from the vent 33 and to seat it to close port 31. Magnet 19 is energized by the depressing of the appropriate key of the manual of the organ. That is to say, for example, the key 21 of the manual of the organ is depressed to the position indicated by broken-lines in Fig. III, and a contact strip 24 on the key is moved to bear upon the contacts 23. Conductors 25 pass to a convenient source of electrical energy and thence to the electrical terminals 20 of the magnet 19, whereupon, by depressing the key 21, the contact strip 24 electrically unites the contacts 23, completing an electrical circuit, and energizing the magnet 19. 90

Fig. I of the drawings shows the parts in position, ready for playing. Wind-chests 1 and 17 are filled with air at super-atmospheric pressure. The stop to which pipe 2 is responsive has been drawn out, and in consequence a condition of reduced pressure has been established in the chest 15 associated therewith. The corresponding valve 14 has accordingly been drawn upward, closing chest 15 but leaving lead 10 open, from chamber 9 to manifold 11. The double valve 12, 13 stands in such position that the manifold 11 is in open communication with wind-box 1. 95

The parts being in this position, when the appropriate key of the organ manual is depressed electro-magnet 19 is energized. The energizing of the magnet causes the shifting of valve 18 to close communication through port 31 between auxiliary wind-box 17 and manifold 11, and to open communication from auxiliary wind-box 17 through vent 33 to the atmosphere. Thereupon the super-atmospheric pressure within wind-box 1, effective upon valve part 12, causes a left-to-right shifting of the compound valve 12, 13, a closure of valve 13, an opening of valve 12, and a venting of manifold 11 to the open air. Thereupon the super-atmospheric pressure within wind-box 1 will be effective, overcoming the force of spring 8, to depress diaphragm 7, and to open valve 6. Wind will then blow through pipe 2 and the pipe will speak. The supply of compressed air to wind-box 1 being unfailing, the pipe will continue to speak, so long as the key continues to be depressed. 100

When the key is released the valve 18 will fall away, opening port 31 and closing vent 33. Thereupon pressure will accumulate in auxiliary wind-box 17, diaphragm 16 will 110

be shifted; the compound valve 12, 13 will return to the position shown in the drawing; pressure in manifold 11 and in wind-box 1 will be equalized, and spring 8 will be effective to close valve 6; and pipe 2 will be silent.

With particular attention to pipe 3 and its associated parts, the stop with which this pipe is associated has not been drawn out.

10 Accordingly the corresponding valve 14 remains free, and acts as a check valve in lead 10. When, following upon the depression of the key of the organ manual the manifold 11 is vented to the air, valve 14 will continue in closed position, and there will be no such disturbance of pressure as to render spring 8 ineffective. Valve 6 will continue closed, and pipe 3 will not speak.

As the stops are shifted one or more of the pipes 2, 3, 4, 5 may be caused to speak, when the appropriate key is depressed. The arrangement of the manifold 11 within the wind-box is of great advantage in minimizing the number and lengths of the passages necessary. It should be noted that a single manifold has been provided for all of the pipes of the wind-box, and, in general, that the instrumentalities for causing the pipes to speak are so organized as to simplify construction and minimize cost.

In the course of this specification the word stop has been used with two distinct significations; but the double meaning prevails in the art, and is unavoidable. The context makes plain in each case, with which meaning the word is used. In one sense the word means a group of pipes—a fraction of the organ; in the other sense it means the manually controlled member on the organ manual, by the shifting of which a particular group of pipes is brought into operative relationship.

We claim as our invention:

1. In a pipe organ the combination of a wind-box, a plurality of pipes communicating with said wind-box, a corresponding plurality of chambers closed by pressure plates which pressure plates externally are subject to wind-box pressure, and a corresponding plurality of valves connected severally to said pressure plates and movable to open and close communication from the wind-box to the said pipes severally, a manifold chamber, conduits from the pressure plate chambers to said manifold chamber, means for establishing communication from said manifold chamber alternately to said wind-box and to the open air, said means including an auxiliary wind-box with a pressure plate in its wall, an orifice opening from said auxiliary wind-box, a valve controlling said orifice and an electro-magnet controlling said valve, a plurality of low pressure chests corresponding in number to said pressure plate chambers and communicating one with each of the conduits leading from said chambers, and a

plurality of valves arranged one in each of said conduits and serving normally as outwardly closing check valves and movable in response to a condition of reduced pressure in the said chests from position for such normal service.

2. In a pipe organ the combination of a wind-box, a plurality of pipes associated with said wind-box, a plurality of pneumatic pressure chambers associated one with each of said pipes and each including a movable pressure plate, the pressure plate in its movement controlling communication between the wind-box and the pipe, a manifold chamber, conduits leading from each of the said pneumatic pressure chambers to said manifold chamber, a check valve in each of said conduits movable to and from checking position, stop-operable means associated with each of said valves and adapted to move the valve from checking position, and key-controlled means for establishing communication from said manifold chamber alternately to the open air and to the wind-box.

3. In a pipe organ the combination with a key and a stop, of a wind-box, a pipe in communication with the wind-box, a valve controlling such communication, a chamber closed by a pressure plate with which pressure plate said valve is connected, said pressure plate on its outer side being exposed to wind-box pressure, said chamber being formed with a metal base portion, a conduit of rubber tubing leading from said chamber, a valve arranged on said base portion for controlling flow through said conduit and movable to and from a position to serve as a check valve, means responsive to depression of said key for venting said conduit to the open air, and means responsive to a shifting of said stop for moving the valve in said conduit from its check-valve serving position.

4. In a pipe organ the combination with a key and a plurality of stops, of a wind-box, a plurality of pipes in communication with the wind-box, a plurality of valves each controlling one such communication, a plurality of chambers closed by pressure plates with each of which pressure plates one of said valves is connected, said pressure plates on their outer sides being exposed to wind-box pressure, a plurality of rubber conduits leading severally from said chambers, said chambers being formed with metal base portions, a plurality of valves arranged one on each of said base portions for controlling said conduits and movable to and from position to serve as check valves in said conduits, means responsive to depression of said key for venting said conduits to the open air, and a plurality of means responsive severally to the shifting of one of said stops for moving the valve in one of

the said conduits from its check-valve serving position.

5. In a pipe organ the combination of a wind-box, a pipe communicating with said wind-box, a chamber closed by a pressure plate, a valve connected to said pressure plate to open and close communication from the wind-box to the pipe, a manifold, and a conduit of rubber tubing from said chamber to said manifold.

6. In a pipe organ the combination of a wind-box, a plurality of pipes communicating with said wind-box, a corresponding plurality of chambers closed by pressure plates, and a corresponding plurality of valves connected severally to said pressure plates and movable to open and close communication from the wind-box to the said pipes severally, a manifold within said wind-box, and a plurality of rubber tubes severally connecting each of said chambers to said manifold.

In testimony whereof we have hereunto set our hands.

ALFRED MOORHOUSE.

SAMUEL G. BOWMAN.
